US0D1036029S

(12) **United States Design Patent** (10) **Patent No.:** **US D1,036,029 S**
(45) **Date of Patent:** **** Jul. 16, 2024**

(54) **GARMENT STEAMER**

(71) Applicant: **Shenzhen Shouzheng Chuqi Technology Co., Ltd.**, Shenzhen (CN)

(72) Inventor: **Mengyi Sun**, Shenzhen (CN)

(**) Term: **15 Years**

(21) Appl. No.: **29/915,491**

(22) Filed: **Oct. 31, 2023**

(30) **Foreign Application Priority Data**

May 9, 2023 (CN) 202330266013.3

(51) **LOC (14) Cl.** **15-05**

(52) **U.S. Cl.**
USPC **D32/17**

(58) **Field of Classification Search**

USPC D32/17-21, 25, 31-34, 35
CPC D06F 75/10; D06F 75/12; D06F 75/14;
D06F 75/16; D06F 75/18; D06F 75/20

(57) **CLAIM**

The ornamental design for a garment steamer, as shown and described.

DESCRIPTION

FIG. 1 is a perspective view of a garment steamer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2;

FIG. 10 is an enlarged view of portion 10 shown in FIG. 2;

FIG. 11 is an enlarged view of portion 11 shown in FIG. 4;

and,

FIG. 12 is an enlarged view of portion 12 shown in FIG. 5. The dash-dash broken lines in the drawings depict portions of the garment steamer that form no part of the claimed design.

The dot-dash broken lines represent boundaries of the enlarged portions and form no part of the claimed design.

1 Claim, 12 Drawing Sheets
